UNITED STATES PATENT OFFICE.

WILLIAM A. PFEIFFER, OF CLEVELAND HEIGHTS, OHIO.

VALVE-LIFTING DEVICE.

Application filed October 15, 1924. Serial No. 743,669.

This invention, as has been indicated, relates to valve spring lifters. More particularly it comprises an implement for simultaneously raising the springs surrounding a plurality of poppet valve stems of a gas engine to permit the removal of said valves and the cleaning and grinding thereof.

In most instances a valve spring lifter comprises an implement operating upon but 10 a single valve spring and a great deal of time is consumed in adjusting the device within the restricted space wherein such valves are located, particularly in automobile motors.

The principal object of the present invention is to improve valve spring lifting implements and to simplify the manufacture and use of the same. A further object of the invention is to provide a device which will simultaneously lift a plurality of valve 20 springs and will thereafter maintain them in compressed condition until the operations upon the valves and engine are completed. Other objects will appear in the course of the following description. To the 25 accomplishment of the foregoing and related ends, said invention, then, consists of the means hereinafter fully described and particularly pointed out in the claims.

The annexed drawings and the following 30 description set forth in detail certain mechanism embodying the invention, such disclosed means constituting, however, but one of various mechanical forms in which the principle of the invention may be used.

In said annexed drawings:—

Fig. 1 is a top plan view of the preferred form of spring lifter embodying the principle of the invention; Fig. 2 is a fragmentary perspective view showing the preferred 40 form of valve spring lifter, the slotted plate being omitted; Fig. 3 is a transverse sectional view of one of the valve spring engaging elements secured in position upon a transverse bar, as shown in Fig. 2, the locking action of the thumb screw being directly against the upper surface of said bar; Fig. 4 is a view similar to Fig. 3 but showing the use of the slotted plate, the locking action being accomplished by the flanged head 45 of the thumb screw against the upper surface of said plate; Fig. 5 is a perspective view showing a modified form of the valve spring lifter; Fig. 6 is a transverse sectional view taken along the line 6—6 shown in Fig. 5 looking in the direction of the arrows; Fig. 7 is a diagonal sectional view taken

along the line 7—7 shown in Fig. 5 looking in the direction of the arrows; and Figs. 8 and 9 are top plan and side elevations respectively of a form of the invention adapted for 60 use upon the adjacent valve springs.

As is clearly shown in Figs. 1 to 4, in the preferred form of the valve spring lifter, a foot plate 1 is adapted to rest upon the upper side of the crank case of an engine which normally constitutes the floor of the valve housing. Said plate preferably has an elongated forward portion or tongue 2 adapted to extend between the centrally positioned valves of the engine, which is provided with 70 a set screw 3 at its inner end whereby said plate may be brought to a level position. The forward portion of said foot plate will rest upon the upstanding flange at the outer edge of the valve housing. Rotatably 75 mounted upon the foot plate adjacent the enlarged body portion thereof, a screw-threaded standard 4 is provided. Said standard is provided with a hexagonal portion 5 adjacent its lower end whereby it may be rotated in either direction for the adjustment of the mechanism hereinafter to be described. The threaded portion of the standard carries a transverse supporting block 6. This block is provided adjacent its inner portion with a screw-threaded vertical aperture 7 which co-operates with the screw-threaded portion of the standard and is beveled at each rearward corner for a purpose 80 presently to be disclosed. The rearward upper surface of said block is of slightly greater height than the forward portion, providing a shoulder 8 at an intermediate position. The body of said block extends forwardly 85 from said standard and is provided on its under side with an upwardly beveled face 9, and on its upper side with a transverse rib 11 parallel to and in spaced relation to the shoulder 8 heretofore described. A transverse keyway 12 is formed centrally through 90 the forward extension of said block and is adapted to slidably receive a pin or a key 14 projecting from a transverse supporting bar 13.

A screw-threaded vertical opening 15 is 105 formed at a point centrally of said upstanding rib and is adapted to receive a thumb screw 16 having a flanged collar 17.

The transverse bar is adjusted as desired, 110 preferably to extend an equal distance to each side of said supporting block and carries in slidable engagement therewith a plu-

rality of valve spring engaging members 18, 19, 20, 21. As is clearly disclosed in the drawing these valve spring engaging members are of two types, the inner members 19, 20, disposed adjacent said supporting block having lateral fork extensions 23, 24, and the outer members 18, 21, having outwardly and oppositely directed fork extensions 22, 25. The inner members have body portions 10 of greater width than the end members and the fork extensions thereof are provided with beveled sides which adapt them to be drawn more closely against the beveled rearward corners of the central supporting block. 15 The body portions of each of the valve spring engaging members are provided with beveled under faces similar to and in alignment with the beveled face of said supporting block and the upper surfaces thereof 20 are provided with transverse integral ribs 26, 27, 28, 29, in alignment with the rib on the upper surface of said supporting block. The ribs 26 and 29 on the upper surfaces 25 of the end spring engaging members preferably do not extend completely across the same for a reason to be hereinafter explained. Through the body portions of each of said spring engaging members vertical screw-threaded openings 31 are provided parallel with the similar opening 15 through the central supporting block and flanged thumb screws 32 similar to the thumb screw 16 provided for said central supporting block are adapted to be engaged 30 in said vertical openings. The device, as thus far described, is suitable for operation as a valve lifting device under certain conditions, the valve spring engaging members being inserted beneath the valve springs by 35 suitable longitudinal adjustment upon the transverse rod and being secured in position through the locking action of the thumb screws, as illustrated in Fig. 3, the lower ends of which are adapted to contact with 40 the upper surface of the transverse supporting rod.

In order to strengthen the construction and simplify the adjustment of the various elements thereof it has been found desirable 45 in some instances to place upon the upper surface of the valve spring engaging members and the supporting block a longitudinally slotted plate 33. As is clearly shown in the drawing this plate preferably is of a 50 length similar to the length of the transverse supporting rod and the slot 34 thereof is of a size to engage over the transverse ribs upon the upper surface of each of said members. The inner edge of said slotted plate 55 is adapted to ride against the shoulder 8 provided on the supporting block and the ends of said slot are adapted to serve as stops when the end spring supporting members are moved outwardly to their extreme 60 limit of outward adjustment. As has been

stated, the ribs 26 and 29 on the outer members do not extend completely across the upper surface thereof and they are preferably rounded at their outer ends to conform to the rounded shape of the ends of said slot. 70 It will be noted that, as illustrated in Fig. 4 particularly, the plate is of greater height than the height of the ribs on the upper surfaces of the respective members heretofore described. This permits of clamping adjustment against said plate through the actions of the flange on the respective thumb screws. Thus, the thumb screws serve as locking members through the action of the flanged collars adjacent their upper portions when the slotted plate is used, and lock, through the contact of their lower ends directly against the transverse bar, when said plate is dispensed with. 80

In the form of construction just described it will be noted that the standard is positioned outwardly of the point of contact of the forks with the several valve springs, thus giving ample clearance for said standard and adequate space for its associated members to perform their necessary functions. 90

In the form of construction disclosed in Figs. 5, 6, and 7, the standard 41 is positioned in substantial alignment with the centers of the valve springs. In said construction a substantially square foot plate 42 is provided on which said standard is rotatably mounted. A supporting block 43 is screw-threadedly engaged upon the upper end of said standard and an actuating hexagonal portion 44 is formed adjacent its lower end. The supporting block is provided with a transverse opening 45 to receive a cylindrical rod 46, and the outer upper surface of said supporting block is cut away to provide a shoulder 47 adjacent the central portion thereof. A longitudinally extending slotted plate 48 is adapted to be secured across the outer portion of said supporting block by means of a stud 49 having its lower end securely mounted in said block and having its upper end projecting through the longitudinal slot of said plate. A nut 51 on the screw-threaded upper end 115 of said stud serves to lock said transverse plate in any desired position of adjustment, a downwardly extending rib 52 is provided on the under side of said plate and is of a size to engage a transverse groove 53 formed in said block adjacent its forward edge. The lower face of said supporting block is preferably beveled to provide ready access to the adjusting head of said standard. 120

As is clearly shown in Fig. 5, a plurality of valve spring engaging members 54, 55, 56, 57, are slidably mounted upon said transverse rod and may be secured in locking engagement with said transversely extending plate. Each of said valve spring engaging members comprises a body portion trans- 125

versely apertured to fit over said supporting rod and a fork portion projecting forwardly thereof. The upper surface of said body portions are provided with transverse grooves 53 in alignment with the groove 53 in the upper face of the supporting block, which grooves receive the longitudinal rib 52 on the under side of the slotted plate. In each of said blocks a stud 59 is rigidly mounted in a position to pass through the longitudinal slot of said transversely extending plate and a wing nut 60 is engaged over the screw-threaded upper end of said stud. The fork portions of the valve spring engaging members project in alignment with the body portions thereof in the case of each of the two centrally disposed members 55, 56, and are turned outwardly and oppositely at right angles to said body portions in the case of the two end members 54, 57.

As is clearly shown in Figs. 8 and 9, a simplified form of construction may be utilized to operate upon two adjacent valve springs, said device comprising a base plate 61 upon which a screw-threaded standard 62 is rotatably mounted, said standard having a hexagonal portion 63 adjacent its lower end whereby the same may be rotated. The upper end of said standard is screw-threadedly engaged within a central aperture of a supporting collar 64. Said supporting collar is provided with flanges at either side adapted to support the side edges of a slotted valve spring engaging member 65. Said member is provided at one end with a longitudinally extending valve spring engaging fork 66 and at its opposite end with a laterally extending valve spring engaging fork 67. The extreme corner of the laterally turned fork is provided with an upturning lip 68. The device is placed in position by first engaging the longitudinally extending fork about its adjacent valve stem and beneath the spring and then moving the laterally extending fork beneath the spring surrounding the adjoining valve stem. The lip 68 upon the laterally extending fork will engage behind the spring and prevent the outward movement of the plate when the valve springs are compressed through the rotation of the standard, as in the case of the other forms of construction. The central slot formed in the plate permits the necessary lateral adjustment to position the standard centrally between the valve springs.

In the form of construction disclosed in Figs. 1 and 5, it is obvious that the device is adapted for the simultaneous raising of four valve springs. To place the device in position the foot plate is carefully adjusted to a firm seating upon the upper wall of the crank case. In the form disclosed in Fig. 1 the screw in the rearward end of the tongue is turned until the device is properly leveled. The forks of the two central members are

then passed beneath the valve springs of the centrally positioned valves of the engine and the outermost valve spring engaging members are moved laterally to engage the same with their adjacent springs. The thumb screws, or wing nuts, are then turned to clamping adjustment and the hexagonal portion of the screw-threaded standard is actuated. When the desired degree of compression has been produced the locking means associating the valve springs with the valve stems is detached and the valves are then free to be withdrawn. When any necessary operations upon the valves, such as grinding or reseating, are completed, the locking elements may be restored prior to the release of the springs.

Thus it will be noted that with a single implement four valves may be simultaneously handled. It will also appear that but a single spring compressing operation is necessary for the completion of the release and re-adjustment of the locking devices operatively associating the springs with the valve stems. The valve springs when under compression will have no tendency to move side-wise, the valve stem guides serving to center the upper ends thereof and the forks being perfectly level and maintaining said springs in compressed condition and free from the danger of lateral movement.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:

1. An apparatus of the character described comprising a vertical standard, a supporting member adjustably engaged therewith, and a transverse member extending through and laterally adjustable with respect to said supporting member and provided with a plurality of valve spring engaging elements.

2. An apparatus of the character described comprising a vertical standard, a supporting member adjustably engaged therewith, and a transversely extending member laterally adjustable with respect to said supporting member and provided with a plurality of valve spring engaging elements each movable laterally independently of said transversely extending member.

3. An apparatus of the character described comprising a vertical standard, a supporting member adjustably engaged therewith, and a transversely extending member laterally adjustable with respect to said supporting member and provided with a plurality of valve spring engaging fork members, the end fork members being turned

at right angles to the intermediate fork members and oppositely to each other.

4. An apparatus of the character described comprising a vertical standard, a supporting member adjustably engaged therewith, and a transversely extending member laterally adjustable with respect to said supporting member and provided with a plurality of valve spring engaging fork members, each 10 movable laterally independently of said transversely extending member, and the end fork members being turned at right angles to the intermediate fork members and oppositely to each other.

15 5. In an apparatus of the character described, the combination of a base plate, a screw-threaded standard rotatably mounted on said base plate, a support screw-threadedly engaged upon said standard and adjustable vertically through the rotation of said standard and extending to one side thereof, a transverse member extending through and engaged with the projecting portion of said support, and valve spring 20 engaging means adjustably supported upon said transversely extending member.

6. In an apparatus of the character described, the combination of a base plate, a screw-threaded standard rotatably mounted 30 on said base plate, a support screw-threadedly engaged upon said standard and adjustable vertically through the rotation of said standard and extending to one side thereof, a transversely extending member 35 engaged with the projecting portion of said support, valve spring engaging means adjustably supported upon said transversely extending member, and means for locking said last-named means in adjusted position.

40 7. In an apparatus of the character described, the combination of a base plate, a screw-threaded standard rotatably mounted on said base plate, a support screw-threadedly engaged upon said standard and adjustable vertically through the rotation of said standard and extending to one side thereof, a transversely extending member slidably 45 but non-rotatably engaged with the projecting portion of said support, and valve spring 50 engaging means adjustably supported upon said transversely extending members and adapted to be locked thereto in adjusted position.

8. In an apparatus of the character described, the combination of a base plate, a screw-threaded standard rotatably mounted 55 on said base plate, a support screw-threadedly engaged upon said standard and ad-

justable vertically by the rotation of said standard and extending to one side thereof, 60 parallel transversely extending members engaging with said support, and valve spring engaging means adjustably supported upon one of said transversely extending members and adapted to be locked to the other of 65 said members.

9. In an apparatus of the character described, the combination of a base plate, a screw-threaded standard rotatably mounted on said base plate, a support screw-threadedly engaged upon said standard and adjustable vertically through the rotation of said standard and extending to one side thereof, a transversely extending rod engaged centrally with the projecting portion of said support, a transversely extending plate having its central portion secured in fixed engagement with the upper face of the projecting portion of said support, and valve spring engaging means adjustably supported upon said rod and adapted to be locked to said transversely extending plate.

10. In an apparatus of the character described, the combination of a base plate provided with a narrow tongue at its rearward end, a set screw engaged through said tongue and providing for the levelling of said base plate, a screw-threaded standard rotatably mounted on said base plate, a support screw-threadedly engaged upon said standard and adjustable vertically through the rotation of said standard and extending to one side thereof and having a body portion, 85 said body portion being provided with a transverse aperture, a transverse supporting member engaged within said aperture and projecting to either side thereof, a transverse rib upon the upper face of the projecting body portion of said support, a transversely extending plate provided with a longitudinally extending slot, a stud bolt projecting upwardly from the body portion of said support and adapted to slidably engage within the slot of said plate, means on the upper end of said stud for locking said plate in adjusted position, a plurality of valve spring engaging members slidably engaged upon said transverse supporting member, and means associated with each of said 90 spring engaging members for locking the same to said transversely extending plate.

Signed by me, this 9th day of October, 1924.

WILLIAM A. PFEIFFER.
